VENDING MACHINE

Ernest W. Handley, Arlington, and Walter Segerstrom, Somerville, Mass.

Application November 21, 1939, Serial No. 305,428

7 Claims. (Cl. 312—67)

The present invention relates to vending machines and in particular to vending machines for vending small packages although the machine of the present invention may be adapted and constructed for packages of any size.

The chief advantages of the present invention reside in the simplicity of construction, lack of complicated control devices, reliability of operation, and the safety provisions whereby the machine may not be operated except in the proper intended fashion.

The machine of the present invention and most of its operating parts are stamped, pressed or die cut out of sheet stock, so that little or no machinery is required. Further there are a great number of similar parts and comparatively few parts in the whole machine. Each section of the machine is the same with only one coin control for all sections of the machine. Each section also contains two compartments, a forward and a rear compartment, both operated by the same mechanism. All of the parts have positive action and springs are used principally to return the mechanism to an inoperative position after the goods have been delivered or the coin returned.

The invention is also featured by a case construction which protects the article to be vended from vermin, rodents and other objectionable insects or animals.

The invention is also characterized by other features and advantages which will be better understood from the following description and the drawings illustrating an embodiment of the invention, in which:

Figure 1 shows a front view of a part of the machine with the front plate removed and with other details shown in fragmentary sections.

Figure 2 shows a side view of the device as shown in Figure 1 with fragments of details shown, parts of the casing being removed and parts shown in section.

Figure 2a is a sectional view of a detail taken substantially on the line 2a—2a of Figure 1.

Figure 3 shows a detail of a portion of the elements shown in Figure 1.

Figure 4 shows a top view of the structure shown in Figure 3.

Figure 5 shows a side view of the elements shown in Figure 3.

Figure 5a shows a section on the line 5a—5a of Figure 4.

Figure 6 shows a view of a detail of the invention.

Figure 7 shows a front view of the detail shown in Figure 6.

Figure 8 shows a detail substantially on line 8—8 of Figure 9 showing the lower portion of the device and the package drawer in transverse section.

Figure 9 shows a front view of the detail shown in Figure 8, and,

Figure 10 shows a sectional view substantially on the line 10—10 of Figure 9.

In Figure 1 which shows the front of the machine from which the front wall of the casing 1 and the operating knobs 2 (see Figure 2) have been removed, it will be seen that there are indicated five independently operating sections with compartment walls as shown by 2' and 3' each of which has a pair of vertically positioned chambers 4 and 5, (Figure 2) containing the packages of the goods to be vended. While each of these sections may be operated independently, nevertheless when any one section is being operated, that is, when the package is being withdrawn after the proper coin has been inserted, none of the other sections may be operated until the operation of that section has been fully completed.

The front of the machine has a plate 6 upon which is mounted a plate 7 which has been pressed to form a series of horizontal and vertical recessions. This plate 7 is mounted on the plate 6 by a group of screws 8, although it may be mounted in other ways if desired, as by means of welding or the like. The plate 7 is provided with a series of vertical recessions 9, one for each of the operating sections and also a horizontal recession 10 intersecting all the vertical recessions and extending the whole length of the plate from one end and almost to the end of the plate at the other end. As the plate 7 is fixed firmly to the wall 6, these recessions form a group of vertical slots between the plates 6 and 7, which vertical slots are closed at the base by the cross member 11 bolted to vertical partitions 12 of the side walls of the machine. The horizontal slot 10 extending the length of the front of the machine is closed at one end where the plate 7 touches the plate 6 and open at the other end as will be presently described. Within the vertical slots 9 there are positioned vertically sliding members 14 which are wedge shaped as indicated at 15 at the lower end of each member. In each of the vertical slots there is a single vertical operating bar or plate. In the horizontal slot there is positioned a succession of independent bars 16 one for each machine section. Each of these bars 16 abuts the other,

end to end in the slot and they are held against one another by means of the spring 17 which is fastened at one end to the outside of the plate 7 and at the other end to the end of the last member 16 which is provided with an upturned or projecting portion 18 about which the hooked end 19 of the spring 17 fastens. The corners of the upper ends of the horizontal bars are cut off at an angle as indicated by 20 and 21, so that as the wedge shaped edge 15 comes down against the bar, it will find its place between the adjacent ends of successive bars. The bars 14 are the selective means whereby only one of the knobs 2 may be turned at a time. When any one of the bars 14 is forced vertically downwards, the horizontal bars 16 are horizontally displaced to the left of the bar 14 which is forced downward so that these horizontal bars to the left of the vertical bar 14 will present, not the edges between the two successive horizontal bars to the wedge end of a vertical bar to the left of the displaced vertical bar 14, but a portion of each bar between its ends which will prevent any downward motion of the vertical bars. The horizontal bars to the right of the vertical bar which has been operated will not yield, since the vertical bar 14, which is operated, passes down below the horizontal groove to the vertical section 22 of the vertical groove below the position of the horizontal bars. The vertical bar in this position, locks all the horizontal bars to the right as viewed in Figure 1 in fixed position and does not allow any of the other vertical bars to be displaced. The vertical bars 14 at their upper end projecting out of the groove 9 have a forwardly projecting flange 23 against which the edge 24 of the cam 25 bears for operating the vertical bars. This cam 25 is fixed to the shaft 26, Figure 2, upon which the knob 2 is mounted. When therefore the vertical bar will not move, the knob cannot be turned, preventing the operation of the sections and the delivering of the package from such sections. The cam 25 is also provided with a forwardly projecting bar 27 which projects sufficiently forward to engage a long horizontal bar 28.

This long horizontal bar is mounted by two horizontal pins 29 and 30, each having oversized heads 31 (Fig. 2) the bar being retained on the pins in the slots 33 and 34 so that the bar 28 may be moved to the right as seen in Figure 1 by the clockwise rotation of the cam 25 as indicated by the arrow 35 through the bearing of the forward projecting bar 27 of the cam 25 against the edge 36 of the recess 37 in the bar 28. The bar 28 has a recess 37 for every section of the machine and the edge 36 of this recess has, bearing against it, a projecting bar 27, except the end section in which the projecting bar 27 bears against the edge 36 at the end of the bar. The operation therefore of any one of the five knobs operating its associated cam 25 will move the bar 28 to the right relative to the slots 33 and 34. At the extreme right of the machine there is positioned a horizontal pivoted arm 38. The arm is shown in Figure 1. This arm bears against a shoulder 39 at the upper corner of the bar 28 so that the operation of the bar 28 to the right will push the arm 38 which is connected with the coin controlled lever as will be explained below. That is to say the arm or lever 38 cannot be moved unless the proper coin has been inserted in the coin chute used with the device.

The coin selector mechanism does not form a part of the present invention and any type of proper coin selector mechanism may be used. A

spring 40 is hooked at one end into a hole 41 of the arm 38 and at the other end about the pin 30 which is mounted in the wall 6 (Fig. 2) of the machine. This spring acts to hold the bar 28 in position against the projecting bars 27 of the cams. When the bar 28 is moved to the right, the spring will stretch. As the arm 38 is pushed to the right and the projecting bar 27 passes beyond the lower corner of the surface 36 releasing the bar 28, the action of the spring 40 will cause the arm 38 to push the bar 28 back into its normal position. As will be seen in Fig. 1, the cam 25 will operate the bar twice for every revolution and after the upper projecting member 27 has operated against a bar 28, the lower projecting bar 27' will next operate the bar 28 when this comes into its proper vertical position.

Figures 3, 4 and 5 show the relationship of the operating mechanism and the coin control device.

As will be seen in Figure 4 the lever 38 is substantially a fan shaped cam and is pivoted on a vertical pivot 43 journaling the lever 38 on the horizontal angle bracket 44 fixed to the plate 6. While the bar 28 bears against the edge 45 of the lever 38, the other edge 46 rests against the coin 47 if the coin happens to be in the coin chute 48 (Figure 5). The coin when in the coin chute acts upon a lug 54 on a bar 49 pivoted to the partition 12 at 50 when the coin is moved by the edge 46 of the lever 38. This movement of the bar 49 by the lever 48 acting on the coin moving it, will raise the projecting shoulder 51 of the lever 49 so that the lever 38 will clear the bar as it is rotated in a counterclockwise direction as indicated by the arrow 52 in Figure 4. If the coin is not in position, then as the lever 38 is rotated, the edge 46 of the lever comes up against the shoulder 51 and no further motion of the lever can be effected. This means that the bar 28 is blocked from further movement and therefore also the operating handles 2 cannot turn. The lever 49 is held down by means of the spring 53 so as to bring a projecting member 54 against a slot 55. The coin 47 bears against the lever 49 through this projecting member 54 which projects from the edge of the lever 49 through the slot 55 made in the wall of the coin chute 48, into the chamber of the chute in which the coin is positioned. As the edge 46 of the lever 38 moves the coin 47 to the right, (Fig. 5), the coin is released by sliding out of the coin chute under the projection 54 whereupon it drops into a coin receiving box not here described. If the machine is emptied, in which case the sections will not operate as will be described below, a knob 56 may be turned which releases the coin from the chamber in the manner described below so that it may be returned to the individual who has deposited it. For this purpose the knob 56 is carried by a shaft 57 journalized in bearings 58 and 59 supported from a side wall of the machine. The shaft 57 carries a small plate 60 upon which the bottom edge of the coin 47 rests. This plate is biased towards the chute supporting frame by means of the spring 61 and through the rotation of the knob 56, this plate 60 is removed from below the coin so as to permit the coin 47 to drop straight down to a delivering draw mentioned below. As has been stated above, when the coin 47 is in the proper position, the lever 49 is freed so that the arm 38 may rotate and the bar 28 may be moved to the right as viewed in Figures 1 and 4. The shaft 57 carries also a plate 200 which rotates with the shaft, which plate has a forwardly pro-

jecting flange 201 which when the shaft is rotated blocks the end of the bar 28 and prevents the operation of the delivery knob 2 and the delivering of a package even though the coin is in proper position for allowing the bar 28 to reciprocate. It is evident therefore if the individual turns the knob 56 to compel the delivery of the coin, he will be unable to turn the knob 2.

The packages to be vended are stored in the chambers formed by the vertical walls 62, 63 and 64, the wall 63 acting as a partition between the forward wall 64 and the rear wall 62. The goods are packed in vertical columns in the chambers 4 and 5, and are delivered through the open bottom by means of the reciprocating tray 65 open at the top and bottom. The tray is supported freely upon a bracket 66 connected to the end partitions 12 which extends horizontally the length of the machine and is of such a width that when the tray 65 is in either extreme position, one edge 67 or 69 of the guiding partition 70 connected to the sides of the tray will coincide with the side edge of the supporting bracket 66.

When a package in column 4 for instance drops down into the tray it comes to rest upon one half of the bracket 66. This will happen in the position of the machine as shown in Figure 2. When following this as will be explained the handle 2 is rotated so that the delivery tray is moved to the left as far as the stop bracket 70', the partition 70 or rather its wall 67 will push the package to the left as viewed in Figure 2, until the package clears the supporting bracket 66, whereupon it will drop into the delivery chute which is below the supporting bracket 66. In this new position of the tray 65, the top portion 71 of the supporting partition in the tray will be clear of the column 5 and the top end of the wall 69 will then be just under the lower end of the wall 63. In this position then the package in the column 5 will drop into the tray 65 and come to rest on the other half of the bracket 66. The package will then be in a position to be vended from the rear delivery chute at the right of the bracket 66.

The mechanism for reciprocating the delivery tray 65 transversely across the columns 4 and 5 is indicated in Figure 2 when taken in connection with Figures 6 and 7. The shaft 26, on which the knob 2 is fastened, is journaled in the wall 6, and carries, at the right hand side of the wall as viewed in Figure 2, a disc 42 which is mounted by means of a bracket attached to the shaft at an angle inclined to the axis of the shaft. This disc 42 is provided with a slot 72 (Figure 1) at its outer periphery, the purpose of which will be described later. The disc 42 has its end positioned in a wedge shaped recess 73 in a plate 74 which is mounted at the middle of the front wall 75 of the delivery tray 65. As the disc 42 is rotated, it is quite obvious that the tray will reciprocate back and forth a distance equal to its extreme positions as shown by the full line and dotted line positions 42 and 42' respectively in Figure 2.

In the full line position indicated in Figure 2, the disc bears against the rear face of the wedge slot 73, while in the other extreme position, namely the position shown in dotted line 42', the disc will bear against the front edge of the slot. This motion of the edge of the disc horizontally in its rotation, is, of course, made equal to one-half the width of the supporting bracket 66 by proper dimensioning of the size of the disc and the inclination thereof. Mounted upon the projecting plate 74 is a lever 76. This lever is mounted for movement in a plane parallel to the vertical

end walls of the reciprocal tray 65 on the plate 74 by means of the bearing 77. The lever carries a semi-circular disc portion 78 which swings in a vertical plane and is positioned adjacent to the plate 74, the disc 78 covering a portion of a wedge slot 73 when the tongue 79 of the lever is in a horizontal position. This is indicated in Figure 6.

When there is no package in the delivery tray, the tongue 79 is held in a horizontal position by means of the spring 80 which is fastened at one end to the bottom of the plate 74 as shown at 81 and at the other end to the lower forward projecting lug 82 of the lever 76. In this position the semi-circular vertical portion 78 of the lever, partially covers the wedge shaped slot 73 and comes into engagement with the slot 72 in the disc 42 so in this position the disc 42 cannot turn. When the tongue 79 is pressed down the semi-circular disc 78 disposed in a vertical plane clears the disc 42 and this is the condition existing when the packages are in the column 4. It will be noted that this mechanism to prevent the operation of the section when the column is empty need be controlled only by the front column since the machine may always be packed so that the rear column will be the first to be emptied and thereby there is no need of a separate or independent control for the rear column.

In addition to the mechanism already described, in connection with Figure 1, it should be noted of course that one half revolution of the knob 2 will produce one half of the complete cycle of the reciprocating tray 65 so that for each revolution of the knob, two packages are vended. The cam 25 therefore is a cam arranged for duplicate operation for a single revolution. As will be noted from Figures 1 and 2 the shafts 26 are provided with a ratchet 83 which permits a clockwise rotation of the knobs 2 as indicated by the arrow 35, but prevents a counterclockwise rotation through the action of the pivoted pawl 84 pivoted at the point 85 and tensioned against the ratchet wheel 83 by means of the spring 86 so that the knob may be operated only in a clockwise direction. It further will be noted that the insertion of the coin in the coin chute freeing the lever 38 permits only one of the selected knobs to be operated, since the operation of this knob will force down the corresponding vertical bar 14 and thereby lock all the other bars in position so that none of them can be operated until the bar which has been operated is released.

As seen in Figure 1, this does not occur until the edge 24 of the cam 25 has moved beyond the projecting flange 23 of the bar 14 and when the cam has moved into this position, the projecting bar 21 has progressed beyond the edge 36 of the slot 37 thus releasing the bar 28 which flies back into its normal position thus permitting the return movement of the lever 38 which releases the lug lever 49 allowing the coin to drop through into the coin reception box and again locking the lever 38 in its nonoperative position. The machine will then only be operable when another coin has been dropped into the coin chute again freeing the lever 38.

A further feature of the machine is the package delivery arrangement which permits the package to be delivered into a drawer which may be freely opened by the operator or user to remove the package which has been vended. When the drawer which is positioned at the lower end of the machine is opened, the passage to the package columns and sections is completely covered and sealed, as explained below so that it is

impossible to reach the goods until they have been dropped through the delivery chute. Further, the machine is so designed that it is substantially completely sealed at all times keeping the goods within the machine free from access by insects, rodents or other animals.

This arrangement is shown in Figures 8, 9 and 10.

In Figure 8 the front of the machine is shown by the wall 90 and the rear by the wall 91. Supported within the machine at the side walls and freely journaled therein as indicated at 92, is a bottom cover plate 93 extending the whole length of the machine, which is shown dotted in a raised position.

As the drawer 95 is pulled forward away from the wall 91, the cover plate 93 is raised to the dotted line position 93' thereby closing the bottom opening of the machine from the back up to a forward inclined wall 96, which at its lower part has a shoulder into which the down turned end 97 of the plate 93 rests. The rear 94 of the drawer 95 is provided with an inclined wall 98 which at its rear end has a vertically projecting section 99 with a turned end 100. The turned end 100 at the back end of the drawer rides under the cover plate 93 as indicated by the dotted line positions of 99 at 99' and 100 at 100'. The drawer itself is tensioned against the back wall 91 by means of the spring 101 which is fastened at one end to the base of the drawer and at the other end to the wall of the machine itself, so that when the drawer is released it will fly back to a closed position. The back of the drawer is partially shortened and open behind the wall 98 to permit free action of the spring 101. The front end of the drawer 102 is provided with a grip 103 and a top projecting flange 104 which is normally adjacent the lower edge 105 of the front cover 90 of the casing.

As indicated in Figure 9, the drawer is supported from the side walls in a recess 106 in the bracket 107 which is attached to the wall. A U shaped projecting flange 108 carried by the drawer, rides in the recess 106.

Having now described our invention, we claim:

1. In a vending machine of the type described, a cabinet having a forward and rear compartment adapted to hold the products to be vended open at the bottom, a reciprocating tray open at the top and bottom and having a central member positioned to extend under a part of either of said compartments, said tray being positioned beneath said compartments, a bracket for supporting the tray, means for reciprocating said tray between the forward and the rear compartments comprising a shaft having an axis in the direction of motion of said tray, a cam operated by said shaft having an effective operating plane at an angle other than normal to the axis, said tray carrying a member having a wedge shaped slot engaging the periphery of said cam whereby when said shaft is rotated said tray will be reciprocated in the direction of said shaft.

2. In a vending machine of the type described, a cabinet having a vertical chamber divided in two vertical compartments, said compartments being open at the bottom, a delivery tray open at the top and bottom and having a cross member in the mid-section thereof extending upwards from the bottom of the tray and adapted to close a portion of the base of said compartments, a fixed bracket extending across the bottom of the tray, spaced symmetrically with the

openings at the bottom of said compartments, means reciprocating said tray longitudinally thereof a distance equal to the width of said bracket whereby the bottom of each compartment is completely opened alternately in alternate extreme positions of said tray and said means for reciprocating said tray being operable by the purchaser of the article to be vended to push said article beyond said bracket for delivering the same.

3. In a vending machine of the type described, a shaft having an operating knob, a cam mounted at the end of said shaft having an operating plane positioned at an inclination to the axis of said shaft, a delivery tray open at the top and bottom having a projecting member provided with a wedge shaped slot therein, the edge of said cam engaging said slot, a pair of vertical chambers positioned directly above said delivery tray, a bracket positioned beneath said delivery tray for supporting it, said bracket being aligned centrally of said vertical chambers, said delivery tray having a cross member positioned directly across the bottom of said chambers whereby longitudinal motion of the delivery tray will expose completely one or the other of said chambers.

4. In a vending machine of the type described, a shaft having an operating knob, a cam mounted at the end of said shaft having an operating plane positioned at an inclination to the axis of said shaft, a delivery tray open at the top and bottom having a projecting member provided with a wedge shaped slot therein, the edge of said cam engaging said slot, a pair of vertical chambers positioned directly above said delivery tray, a bracket positioned beneath said delivery tray for supporting it, said bracket being aligned centrally of said vertical chambers, said delivery tray having a cross member positioned directly across the bottom of said chambers whereby longitudinal motion of the delivery tray will expose completely one or the other of said chambers.

5. In a vending machine of the type described having a compartment for the storage of the articles to be vended, means forming a delivery opening positioned at the bottom of said machine, a drawer closing the bottom of said machine and positioned to receive the article to be vended, a pivoted partition extending from the rear of said machine into said drawer at an inclined angle and means operatively associating said partition and said drawer whereby said partition is raised to cover the entire opening across the bottom of said machine when the drawer is extended.

6. In a vending machine of the type described having a compartment for the storage of the articles to be vended, a means forming a delivery opening positioned at the bottom of said machine, a drawer closing the bottom of said machine and positioned to receive the article to be vended, a pivoted partition extending from the rear of said machine into said drawer at an inclined angle and means operatively associating said partition and said drawer whereby said partition is raised to cover the entire opening across the bottom of said machine when the drawer is extended and spring means positioned at the rear of said drawer for automatically returning the same when it has been released.

7. In a vending mechanism of the type described, in combination a shaft, a cam carried by said shaft having a plane of operation inclined

with the axis of said shaft, a delivery tray having a projecting element with a wedge shaped slot therein in which said cam engages, said cam having a notch cut at the periphery thereof, a lever having one end positioned in said tray and having a portion in one position covering a portion of said wedge shaped slot and engaging said

notch for preventing movement of said cam and consequent rotation of said shaft except when a package to be vended is in said tray and depresses the lever freeing said portion thereof from engagement with said cam.

ERNEST W. HANDLEY.
WALTER SEGERSTROM.
